PERIMETER TRIM FOR CHALKBOARD OR THE LIKE

John A. Cook, Montreal, Quebec, Canada, assignor to
Vilas Industries Limited, Cowansville, Quebec, Canada

Filed Jan. 23, 1967, Ser. No. 5,518

Term of patent 14 years

Claims priority, application Canada July 22, 1966

(Cl. D13—6)

FIGURE 1 is an end view in elevation of the perimeter trim for a chalkboard or the like according to my new design.

FIGURE 2 is a side view in elevation of the perimeter trim shown in FIGURE 1.

FIGURE 3 is a top plan view of the perimeter trim shown in FIGURES 1 and 2.

FIGURE 4 is an elevation view of the other side of the perimeter trim shown in FIGURE 1.

FIGURE 5 is a bottom plan view of the perimeter trim shown in FIGURE 1.

I claim:

The ornamental design for a perimeter trim for chalkboard or the like, as shown.
